CLAIM

The ornamental design for a storage container, as shown and described.

DESCRIPTION

FIG. 1 is an overhead perspective view of a storage container.

FIG. 2 is a top plan view of the storage container.

FIG. 3 is a bottom plan view of the storage container.

FIG. 4 is a front elevation view of the storage container.

FIG. 5 is a rear elevation view of the storage container.

FIG. 6 is a left side elevation view of the storage container; and,

FIG. 7 is a right side elevation view of the storage container. The broken lines illustrate portions of the storage container and form no part of the claimed design.
